UNITED STATES PATENT OFFICE.

HENRY BORGmann, OF WASHINGTON, DISTRICT OF COLUMBIA.

MOVABLE FOOT REST FOR BOOTBLACK STANDS.

Application filed April 18, 1925. Serial No. 24,157.

To all whom it may concern:

Be it known that I, HENRY BORGmann, a citizen of the United States, residing at Washington, in the District of Columbia, 5 have invented a new and useful Movable Foot Rest for Bootblack Stands, of which the following is a specification.

By way of explanation, it may be stated that when a person ascends to a chair, on a 10 bootblack stand, or descends from a chair, the garments of the person frequently are torn by being caught on the foot rest of the stand; and in any event, the foot rest is in the way, after the occasion for its use has 15 passed. The foregoing being understood, this invention aims to provide a novel means whereby a foot rest on a blacking stand may be turned back into an inoperative and out of the way position when not in use.

20 It is within the province of the disclosure to improve generally and to enhance the utility of devices of that sort to which the invention appertains.

With the above and other objects in view 25 which will appear as the description proceeds, the invention resides in the combination and arrangement of parts and in the details of construction hereinafter described and claimed, it being understood that 30 changes in the precise embodiment of the invention herein disclosed may be made within the scope of what is claimed without departing from the spirit of the invention.

In the accompanying drawings:—

35 Figure 1 shows in front elevation, a blacking stand embodying the present improvements, the foot rest being swung back into an inoperative position;

40 Figure 2 is a vertical section on an enlarged scale, the foot rest being shown in solid line in working position;

Figure 3 is a plan disclosing the shaft and parts associated therewith;

45 Figure 4 is an elevation of the latch and attendant parts, portions being in section;

Figure 5 is a perspective view of the bracket which carries the latch.

In the drawings, there is shown a blacking stand 1 which may be constructed in any 50 desired way. As shown, however, the blacking stand includes sides 2 carrying a platform 3, and carrying, also, a step 4 disposed below and in front of the platform, the blacking stand comprising a front panel 5 located below the step 4, at the front of 55 the stand. In the front portion of the

stand, between the step 4 and the platform 3 there is an opening 6. A seat 7, which may be of any desired sort, is mounted on the platform 3.

60 Bearings 8 are secured to the under surface of the platform 3 in close relation to the sides 2. In the bearings 8, a horizontal shaft 9 is mounted for rotation. Foot rests 10 are supplied, these foot rests including 65 a curved arm 11 and a tread plate 12 mounted on the outer end of the arm. The arms 11 are located close enough to the bearings 8, so that the shaft 9 cannot move endwise in the bearings. The numeral 14 designates 70 a curved keeper including a hub 15 receiving the shaft 9. The keeper is adjustable either longitudinally of the shaft, or circumferentially of the shaft, so that the keeper may be made to cooperate with a 75 latch hereinafter described, and to the end that the latch may be located in various accessible places. A set screw 16 is threaded into the hub 15 of the keeper 14, and, co-operating with the shaft 9, holds the keeper 80 in any position to which it may have been adjusted. At its forward end, the keeper terminates in a finger 17.

85 A bracket 18 is provided, the same being shown in detail in Figure 5. The bracket 18 comprises a plate-like body 19 secured to the under surface of the platform 3, at a point slightly in front of the shaft 9, the body having depending ears 20. In one edge of the body 19 of the bracket 18 there 90 is a seat 21. In the opposite edge of the body there is a seat 22 which is considerably shallower than the seat 21. The ears 20 of the bracket 18 are connected by a pivot element 23 whereon a latch 24 is mounted 95 for swinging movement in a vertical plane, the latch 24 practically filling the space between the ears 20. The latch 24 is supplied in its rear edge with a recess 25 defining an upstanding lug 26. At the upper end 100 of the latch 24 there is a stop finger 27 received in the recess or seat 21 of the body 19 of the bracket 18. The numeral 28 designates a spring tongue. The lower end of the spring tongue 28 is connected by a 105 securing element 29 to the latch 24, the upper end of the spring tongue being received in the recess 22 of the bracket, so that the spring tongue cannot swing on the securing element 29, should the securing element 110 become loosened slightly, it will always remain in operative relation to both the latch

and the bracket which carries the latch. A retainer 30 is mounted in the ears 20 of the bracket 18, in front of the stop finger 27 of the latch 24. About the retainer 30 is disposed a coiled spring 31, the ends of which are mounted in openings 32 formed in the body 19 of the bracket 18 and in the upper portion of the latch 24. The springs 31 and 28, obviously, tend to swing the latch 24 backwardly into the position shown in Figure 4, until the stop finger 27 of the latch abuts against the body 19 of the bracket 18, within the seat 21.

Assuming that the foot rest 10 is in an inoperative position within the contour of the blacking stand, the operator may swing the foot rest forwardly and upwardly, into the position delineated in Figure 2, the keeper 14 engaging automatically with the latch 24, the latch tilting or swinging, to permit the finger 17 of the keeper to engage with the lug 26 of the latch. By pulling the lower end of the latch 24 forwardly, the latch may be disengaged from the keeper 14, and, thereupon, the foot rest will swing down.

Having thus described the invention, what is claimed is:—

1. In a device of the class described, a shaft, means for mounting the shaft for rotation, a foot rest carried by the shaft, a keeper, means for mounting the keeper on the shaft for adjustment longitudinally of the shaft and circumferentially of the shaft, and a latch wherewith the keeper engages, to hold the foot rest in an operative position.

2. The combination with a blacking stand

including a substantially horizontal platform and a seat carried by the platform and spaced vertically from the platform, of a shaft supported for rotation upon the undersurface of the platform, a depending latch supported from the undersurface of the platform and located in front of the shaft, a foot rest mounted on the shaft, and a keeper projecting from the shaft and adapted to cooperate with the latch to hold the foot rest advanced, the latch, the foot rest and the keeper being located entirely to the rear of the forward edge of the platform when the foot rest is in an inoperative position, the stand being open at the front, and being of sufficient height to permit the foot rest to swing freely downwardly into an inoperative position.

3. In a device of the class described, spaced bearings, means for securing the bearings to the undersurface of a support, a shaft journaled in the bearings, foot rests carried by the shaft and cooperating with the inner edges of the bearings to prevent the shaft from moving endwise, a latch, means for mounting the latch movably in a substantially vertical position on the undersurface of a support, and a keeper carried by the shaft and cooperating with the latch to hold the foot rests in an advanced position, the latch being located in front of the shaft and between the bearings.

In testimony that I claim the foregoing as my own, I have hereto affixed my signature.

HENRY BORGmann.
